UNITED STATES PATENT OFFICE.

DANIEL J. MURNANE, OF KIRKWOOD, MISSOURI, ASSIGNOR TO ST. LOUIS PLATE GLASS COMPANY, OF VALLEYPARK, MISSOURI, A CORPORATION OF MISSOURI.

MACHINE FOR GRINDING OR POLISHING GLASS.

SPECIFICATION forming part of Letters Patent No. 761,597, dated May 31, 1904.

Application filed October 7, 1903. Serial No. 176,073. (No model.)

To all whom it may concern:

Be it known that I, DANIEL JAMES MURNANE, of Kirkwood, St. Louis county, Missouri, have invented a new and useful Machine for Grinding or Polishing Glass, of which the following is a full, clear, and exact description, reference being had to the accompanying drawings, forming part of this specification, in which—

10 Figure 1 is a partial side elevation, partly in section, of my improved grinding and polishing machine; and Fig. 2 is a top plan view of the runner, partly broken away. Fig. 3 is a plan view of the working face of the runner.
15 My invention relates to machines for grinding or smoothing plate-glass, and more especially to machines having gravity-blocks carried by the runners of the general type shown and described in my Patent No. 723,008, dated
20 March 17, 1903.

The invention consists in simplifying and improving the gravity-block system by the use of a single block, preferably of annular form, which extends around the center of the runner and is arranged to perform the grinding and smoothing operation, and it further consists in the construction and arrangement of the runner and gravity-block, as hereinafter more fully described and claimed.

30 In the drawings, 2 represents the glass-supporting table, which may be removably mounted on a frame adapted to be rotated. The runners, of which one or more may be used, though I preferably use two of different diameters, are keyed to vertical shafts 3, journaled in the machine-frame 4, in such manner that they can be suspended above and lowered upon the surface of the glass by means of lifting-levers or other devices 5 of ordinary form.
35 The shafts 3 are driven by suitable gearing 6, preferably so arranged that the runners are rotated at a greater rate of speed than that of the table. Thus the table may be rotated at two or more revolutions per minute, while I
40 prefer to use a peripheral speed of several thousand feet per minute for the runners.
45

I have shown each runner as having a hub

7, which is keyed to the vertical shaft 3 and has a series of outwardly-projecting arms 8, connecting to an outer annulus 9. The lower portion 7' of the hub projects below the supporting-annulus and has feather or spline connections 9' with an annular block 10. I have shown two of these feather or spline connections, which allow the annular block to adjust itself vertically, while causing its rotation when the runner is rotated. The block is preferably built up of ribbed castings, the ribs 11 extending to the outer circular flange or rim 12. I have shown the gravity-block as provided with a surface consisting of wooden blocks or pieces 13, bolted to the under side and receiving the bolts which hold the metal runner-bars 14, constituting the grinding or smoothing surface. The projections which constitute the working face of each runner-bar instead of being square in outline, as heretofore, are formed with acute angles 7 at their inner end, as shown in Fig. 3, so that square faces are not afforded at those places for lodgment of the abrasive material and the projections will clear themselves therefrom under the centrifugal action of the runner. I am thus enabled to change the abrasive material from coarser to finer grades from time to time, as required, without incurring the damage which results when coarser abrasive adheres to the runner-bars and scratches the glass during the use of a finer abrasive.

In order to raise the gravity-block from the glass when the runner is lifted, I preferably connect it loosely to the annulus and the runner by swinging eyebolts 15, extending through holes or slots in the annulus and having adjustable nuts or upper portions. As these bolts pass loosely through the supporting ring or annulus, the block can rest by gravity upon the glass, and thereby adjust itself to the glass-surface, and by adjusting the bolts the face of the block can be brought to a position of perfect parallelism with the glass.

In operating the machine the table with the glass secured thereon is brought under the runners, and the runners are lowered, so that

the gravity-block of each engages the surface of the glass. The blocks will then be freed from the supporting action of the bolts and rest by gravity on the glass. The runners are then rotated, while the table is also rotated or, if desired, given a reciprocatory or other movement.

The advantages of my invention result from the simplifying of the system, the rapidity of 10 grinding, and the gravity adjustment of the block, which reduces liability of breaking or injuring the glass. It will be noted that the gravity-block is held by the connections in its own horizontal plane, so that it will maintain 15 a position parallel to the surface to be ground.

Many changes may be made in the form and arrangement of the table, the runners, the blocks, and their connections without departing 20 from my invention.

I claim—

1. A grinding or polishing runner comprising a driving-frame, and an annular gravity-block rotated by said frame and arranged to 25 adjust itself by gravity; substantially as described.

2. A rotary grinding or polishing runner having a driving-frame, and an annular gravity-block connected with the frame in the

horizontal plane of the block; substantially 30 as described.

3. A rotary grinding or polishing runner having a driving-frame and an annular gravity-block with a driving connection between said block and frame arranged to allow up- 35 and-down movement of the block while rotating; substantially as described.

4. A rotary grinding or polishing runner having an annular gravity-block connected with and rotated by a runner-frame and capable of vertical movement therein and an independent suspending device arranged to lift the block with the runner-frame; substantially 40 as described.

5. A rotary runner having projecting working faces formed with acute angles at their inner ends; substantially as described. 45

6. In a grinding or polishing machine, a rotary runner having an annular gravity-block and a series of vertically-adjustable 50 bolts by which it is adjusted and upheld; substantially as described.

In testimony whereof I have hereunto set my hand.

DANIEL J. MURNANE.
